(57) **CLAIM**

The ornamental design for a book-shaped speaker system for handheld digital media player, as shown and described.

DESCRIPTION

FIG. 1 is a front left perspective view of a book-shaped speaker system for handheld digital media player according to our new design;

FIG. 2 is front left perspective view thereof, without the handheld digital media player;

FIG. 3 is a front left perspective view thereof, with the front cover closed;

FIG. 4 is a top view thereof, with the top cover removed; and,

FIG. 5 is a bottom view thereof, with the bottom cover removed.

The broken lines shown in the drawings are for illustrative purposes only and form no part of the claimed design. The back and bottom cover are flat and unornamented.
